DISPENSING MACHINE

Charles C. Kuhl, South Bend, Ind.; Hazel O. Kuhl, administratrix of said Charles C. Kuhl, deceased, assignor, by direct and mesne assignments, of one-half to Hazel O. Kuhl, St. Joseph County, and one-half to George A. Yuncker, South Bend, Ind.

Application February 10, 1941, Serial No. 378,137

13 Claims. (Cl. 312—48)

This invention relates to improvements in dispensing machines, and more particularly to coin controlled dispensing machine by means of which bottles may be sold.

The primary object of the invention is to provide a simple and effective device for automatically dispensing bottles, one by one, responsive to individual deposits of a coin.

A further object is to provide an automatic dispenser which is substantially trouble free in operation.

A further object is to provide a dispensing device with means for controlling the operation thereof, which are so constructed and arranged as to prevent release of the article to be dispensed by any means or by any handling of the machine except by the deposit of a proper coin.

A further object is to provide a device with electrically controlled means, including a tilttable master control switch, which is normally closed but which opens upon shaking or tilting the device.

A further object is to provide a device with a coin selector having means for returning a coin and means for closing an operating circuit according to whether the device is loaded or empty.

A further object is to provide a dispensing device with novel means for carrying and delivering bottles.

A further object is to provide a dispensing device with means for returning coins if the article carrier thereof is empty.

A further object is to provide a dispensing device with control means constructed and arranged to permit a coin to energize a drive member for actuating a dispensing mechanism to discharge an article of merchandise, wherein the discharge of said article serves to actuate means for stopping the operation of the dispensing mechanism.

A further object is to provide a device of this character having an inclined bottle carrying reel with radial partitions defining compartments, each adapted to receive a plurality of bottles, wherein a portion of the cylindrical wall at the lower end of the reel is cut away and is closed by a stationary annular member having a discharge opening through which bottles may pass endwise.

A further object is to provide a device of this character with switch means adapted to be energized by the weight of a coin to energize an operating circuit, with spring pressed means controlled by a normally energized coil connected in said circuit in parallel with said switch means for

holding the coin in position to close the switch, and with a second normally closed switch adapted to be opened by the passage of an article of merchandise from the device, wherein opening said second switch deenergizes the coil circuit to permit the spring pressed means to release the coin from the position in which it holds the first switch closed.

A further object is to provide a device utilizing 10 a plurality of tilttable mercury switches for a control circuit whereby tampering with the dispenser as by shaking or tilting the same will open one or more of the switches required to be closed for dispensing operation.

15 A further object is to provide a device of this character with means for automatically disconnecting the coin control of the device when the same is being serviced.

A further object is to provide a device of this 20 character having means operating automatically to close the discharge chute of the device while the same is being serviced for the purpose of refilling the article carrying reel.

Further objects will be apparent from the description, drawings and appended claims.

In the drawings:

Fig. 1 is a view of the dispenser in front elevation.

30 Fig. 2 is an enlarged fragmentary view of the dispenser with the end of the housing broken away and with the article carrying member illustrated in cross-section.

Fig. 3 is an enlarged fragmentary transverse sectional view of the article carrier of the dispenser.

Fig. 4 is an enlarged fragmentary longitudinal sectional view taken on line 4—4 of Fig. 3.

Fig. 5 is an enlarged fragmentary sectional view of the bottle discharge passage on line 5—5 40 of Figure 3 illustrating one embodiment of the switch for stopping operation of the device.

Fig. 6 is an enlarged perspective detail view of the means for indicating the filled condition of the device.

45 Fig. 7 is an enlarged view in front elevation of the coin receiver and related mechanism.

Fig. 8 is a fragmentary sectional view taken on the broken line 8—8 of Fig. 7.

Fig. 9 is an enlarged detail perspective view 50 of one of the parts associated with the coin receiver.

Fig. 10 is a wiring diagram of the device.

Fig. 11 is a fragmentary sectional view similar to Fig. 3 and illustrating a modified embodiment 55 of the invention.

Fig. 12 is a schematic perspective view of the parts of the device constituting the modified embodiment referred to in Fig. 11.

Fig. 13 is a fragmentary view of the dispenser with the front of the housing broken away.

Referring to the drawings which illustrate the preferred embodiment of the invention:

The numeral 15 designates a housing which is preferably provided with an outer metal wall 16, an inner metal wall 17, and insulation material 18 interposed between said inner and outer walls. A suitable access opening 160 is provided in the housing at one end thereof. The front of the housing mounts a coin receiver 19 provided with a coin return member 20. Also at the front of the housing is mounted a face plate 21 having a bottle discharge opening (not shown) therein. The stop plate 22 fits over the opening in face plate 21 and is pivotally mounted to said face plate at 23. The face plate also provides a chute or trough 24 down which a bottle may slide to bear against the end plate 25.

Within the housing 15 a reel 26 is journaled upon suitable brackets 161 by means of an inclined shaft 27 which extends parallel to the front of the housing and whose lower end is spaced above and substantially in back of the face plate 21. Reel 26 comprises a cylindrical member 28 from which a plurality of radial plates 29 project inwardly to an inner cylinder 30 to define a plurality of longitudinal elongated tapering compartments within the reel, each adapted to receive a plurality of bottles. Adjacent the outermost end of each plate 29 is mounted an angle iron 31 for purposes to be hereinafter set forth. The plates 29 extend beyond the lower end of the cylinder 28 and carry an end plate 32 fixed thereto. Suitable brackets 34 serve as means to support an annular member 35 encircling carrier 26 at the portion thereof between the end of cylinder 28 and plate 32.

The annular member 35 is substantially concentric with the reel 26 at the upper portion thereof and is of an enlarged eccentric radius at the lower portion thereof for purposes to be herein-after set forth. Annular member 35 has an opening therein which communicates with an inclined passageway 36 extending forwardly and downwardly to the front wall of the housing to communicate with the bottle opening in face plate 21. One wall of the passage 36 is projected at 37 adjacent the lower edge of cylinder 28 to extend within the outline of said cylinder in counterrotational direction and form a divider as best illustrated in Fig. 4. To accommodate this divider each of the plates 29 is cut out at 38 as illustrated in Fig. 4. It will also be noticed in Fig. 4 that the angle members 31 terminate adjacent said cut-out 38.

A bracket 39 is mounted within the housing and supports motor 40. The shaft 41 of the motor 40 serves to drive a suitable speed-reducing means (not shown), which is connected by means of chain or belt 42 with a pulley or sprocket on the reel 26 for the purpose of rotating said reel at a reduced speed.

It will be observed from the above that when bottles are placed within the various compartments of the reel defined by the partitions 29 thereof, said bottles will tend to slide toward the lowermost end of the reel. This sliding movement is guided by the angle members 31 which serve to hold the bottles against angular displacement from desired radial position and at the same time to accommodate sliding movement

of the bottles as aforesaid. The rearmost bottles at the lower side of the reel beyond the end of the cylinder 28 serve to slide upon the annular member 35, and as each longitudinal compartment 5 comes into register with passage 36, the rearmost or lowermost bottle in said compartment is permitted to discharge endwise through passage 36. As illustrated in Fig. 4 the adjacent bottles in the compartment which registers with discharge passage 36 are prevented while the reel is in that position from passing to the lower end of the reel by the divider plate 37 and the angle members 31. Thereafter, as the reel is rotated in counter-clockwise direction as viewed in Fig. 3 the lowermost bottle in the compartment which is just leaving registration with passage 36 will pass beyond the divider 37 and thereupon will be permitted to slide to the lower end of the reel against the end plate 32 in which position it will bear upon the annular member 35. The construction of the bottle carrying reel as aforesaid affords advantages of compact storage of bottles in position for accurate discharge thereof through the passage 36 when the successive compartments are brought into register with said passage. Previous devices for discharging bottles have not had the facility for compactness, simple and easy bottle discharge, and control of discharge of one unit only at a time as is provided in this particular construction.

Referring to Figures 7 to 9 inclusive, the coin receiver 19 is illustrated as of that type known commercially in the trade as the National slug rejector. This type of construction has a coin passage 45 extending downwardly therethrough and a coin return passage branching from said passage 45. A coin guide 46 comprises a pair of U-shaped plates in inverted relation with their arms 47 extending downwardly in spaced parallel relation and a vertical web 48 interconnecting arms of one set. A plate 49 interconnects the lower ends of the arms 47 which are also interconnected by the end plate 48 and said plate 49 is bent downwardly to terminate below the other 40 set of arms 47. A web 50 may interconnect the free end of plate 49 with one of the adjacent arms 47. The guide 46 is so located on the coin receiver 19 that a coin discharged therefrom passes between the arms 47 of said guide to fall upon the plate 49 and then bounces from said plate 49 between the arms 47 and into the end of a coin chute 51 leading to a suitable coin box (not shown). The coin return passage is adapted to feed a coin into the return chute 20. It will be understood that coin return chute 20 is positioned exteriorly of the housing 15, while the coin guide 46 and coin chute 51 are housed in sealed relation by the housing 15 and the housing enclosing the coin receiver 19.

An elongated arm or plate 52 is provided with a bracket 53 at one end thereof which is pivoted at 54 to coin return 20. The arm 52 extends to a point between the arms 47 of coin guide 65 46 and terminates in an inwardly directed end portion 52' which passes between said arms 47 and below the discharge end of coin passage 45 of the coin receiver. Bracket 53 mounts a suitable clamp 55 which carries a mercury switch 56. The pivot mounting of the arm 52 is so positioned with respect to the center of gravity of the assembly consisting of the arm 52, bracket 53 and mercury switch 56 that the arm 52 is positioned in an angularly upwardly inclined direction with its end portion 53 bearing against

the bottom of the coin receiver 19. The switch 56 is preferably mounted parallel to arm 52 so that when in normal overbalanced position as illustrated in full lines in Fig. 7, the mercury 57 therein will be located at the end of the switch opposite the end at which the contacts 58 of the switch are located. In other words, switch 56 is so-mounted that it is normally maintained in open contact relation. The unbalance of the arm 52 is very slight and is adapted to be overcome by the weight of a coin 59 falling thereon guided by the guide 46. Hence, the coin serves as means to tilt the arm 52 to dotted line position illustrated in Fig. 7 thereby tilting the switch 56 whereby the mercury 57 serves to immerse the inner ends of the switch contacts 58 to closed circuit position.

A bracket 60 is fixedly mounted on the coin receiver 19 at a point intermediate the height thereof and this bracket serves to fixedly mount electro-magnetic coil 61. An armature member 62 is pivoted to bracket 60 at 63. The armature includes a projection 64 adapted for engagement by a tension spring 65 whose opposite end is carried by a projection 66 fixedly carried by bracket 60. Hence it will be observed that when the coil 61 is deenergized the spring 65 will serve to tilt the armature 62 away from the coil 61. The coil 61 is of a strength or value sufficient to overcome the tension of spring 65 when the coil is energized. The armature 62 fixedly mounts a member 67 extending substantially horizontally and inwardly therefrom. At its inner end the member 67 has an upwardly projecting portion 68 which terminates in an inwardly directed end portion 69 extending in the direction of the coin receiver 19 but terminating in spaced relation thereto. Member 67 also has depending therefrom an arm 70 terminating in a horizontal member 71. The arm 70 and end member 71 are so positioned that when the coil 61 is energized said members 70 and 71 will serve to hold a coin passing into guide 46 in the dotted line position illustrated in Fig. 7 which prevents the coin from discharging into the coin chute 51. However, when the armature 62 is released by the coil and pivoted by the spring, the arm 70 assumes dotted line position illustrated in Fig. 7, which permits coin 59 to drop by gravity into the coin chute. It will be understood that as the coin is dropped into the guide 46 it has depressed arm 52 and that when held by said arm 70, 71, the coin 59 continues to hold the arm 52 depressed.

The coin receiver mounts an elongated spring member 72 adjacent the free end 69 of member 67, said spring member 72 including spring 73 spaced outwardly from the coin receiver and carrying at its lower end an inwardly extending pin 74 adapted to pass through an opening 75 in one of the walls of the coin receiver. The spring 72, 73 normally holds pin 74 in a position as illustrated in full lines in Fig. 8, whereby it is adjacent to the coin passage 45 but does not interrupt the same. The particular location of the pin 74 in the coin passage 45 is at the point at which the coin return passage (not shown) with which the coin return chute 20 is connected branches from said passage 45. It will be observed from Figs. 7 and 8 that when the device is in the full line position, the end 69 of the member 67 will be free from the spring member 72, 73, permitting the pin 74 to maintain its normal inoperative position. However, when the coil 61 is deenergized permitting member 67 to be pivoted with the armature 62 by spring 65, 75 a bracket 98 therein which carries an anti-tilt

5 the member 69 is swung downwardly to engage and press inwardly upon the portion 73. In so doing the pin 74 is pushed into the coin passage 45 as illustrated in dotted line in Fig. 8. This 10 serves to interrupt the coin passage 45 so that any coin which is inserted into the machine while the pin 74 is depressed is diverted by said pin to the coin return passage for discharge at the coin return chute 20.

15 Referring now to Figs. 3 and 6, the article discharge passage 36 mounts a bracket 76 which journals a shaft 77 carrying in turn a fixed arm 78 extending perpendicularly thereto. One end of arm 78 projects from shaft 77 in an upward direction and terminates in an angularly bent portion 79 which carries an elongated arm 80 substantially parallel to shaft 77. One end of arm 80 may be outwardly bent at 81 as illustrated in Fig. 6. The opposite end of the arm 78 projects downwardly from shaft 77 and terminates in a bracket 82 mounting a mercury switch 83. A coil spring 84 encircles shaft 77 and is connected at its opposite ends to bracket 76 and shaft 77 in such a way as to normally rotate the shaft 77 in a counter-clockwise direction when viewed in Fig. 6. The arm 80 is so positioned that it may be urged laterally into the guide ring 35 when the carrier 26 is empty but is normally forced outwardly against the action of spring 84 20 when bottles 85 and 86 are carried upon annular member 35 in a position to be discharged through the discharge passage 36 upon the succeeding operations of the device. The mercury switch 83 is so mounted by the bracket 82 on arm 78 that 25 when the bottles 85 and 86 urge arm 80 outwardly, the mercury therein closes the circuit between the contacts 87 of said switch, but when the spring 84 urges the arm 80 into the ring 35 when no such bottles 85 and 86 are within the carrier, the switch 83 is tilted to a position such 30 that the mercury therein flows to the opposite end of the switch tube and breaks the circuit between contacts 87.

35 Referring now to Figs. 3 and 5: Means are shown therein for operating a mercury switch 88 response to the discharge of an article through the passage 36. In the form illustrated in Fig. 3, an arm is pivoted at 89 on a suitable bracket carried by passage 36 with one end 90 thereof 40 extending through an opening 91 in the passage 36 and the other end thereof carrying brackets 92 mounting mercury switch 88. The arm is normally positioned as illustrated in full lines whereby the mercury within the switch flows to the 45 end of the switch with which the contacts 93 are connected. It will be observed that when an article such as a bottle is discharged through passage 36 the same will strike the end 90 of the switch mounting arm to tilt the same to a position 50 wherein the mercury will flow to the end of the switch opposite that mounting the contacts 93. In the modified construction illustrated in Fig. 5, the passage 36 has a slot 91 therein through which passes an arm 94 mounted 55 upon a rotatable shaft 95 extending transversely below to passage 36. Shaft 95 mounts brackets 96 which carries a mercury switch 97. The operation of this modified device is the same as the preferred embodiment inasmuch as 60 the switch 97 is normally tilted to closed position, and when the arm 94 is struck and pivots shaft 95, the switch 97 is tilted to open circuit position.

65 Referring to Fig. 2, the housing 15 mounts 70 a bracket 98 therein which carries an anti-tilt

mercury switch 88 normally in closed circuit position whose operation is set out hereafter.

It will be understood that housing 15 is of the usual type for dispensing the particular commodities to be contained therein. Thus, for example, if the dispenser is to be employed for vending or dispensing soft drinks, the housing 15 may have contained therein suitable refrigerating and storage means which are not shown herein.

Figure 10 illustrates the wiring diagram of the device. As best illustrated in this figure, line leads 100 and 101 are connected to a suitable terminal block 102 within the device at terminal posts 103 and 104, respectively. A lead 105 is connected with terminal post 103 and is connected with one contact of the mercury switch 88. The other contact of said switch 88 is connected by a lead 106 with terminal post 107 of a terminal block 108 juxtaposed to coin receiver 19. A lead 109 is connected with terminal post 107 and extends to a signal light 109' suitably mounted upon the housing in an exposed position as a position on or adjacent coin receiver 19. A lead 110 extends from signal light 109' to a terminal post 111 on the terminal block 108. A second lead 112 is connected with the terminal post 107 and extends to electromagnetic coil 61, and said coil 61 is connected by a lead 113 with terminal post 114 of terminal block 108. A third lead 115 is connected with terminal post 107 and extends to one of the contacts 58 of the mercury switch 56. The other contact 58 of switch 56 is connected by a lead 116 with terminal post 116' of terminal block 108. Terminal post 111 is connected by a lead 117 with terminal post 118 of terminal block 102. Terminal post 114 of terminal block 108 is connected by a lead 119 with terminal post 120 of terminal block 102. Terminal post 116' of terminal block 108 is connected by a lead 121 with terminal post 122 of terminal block 102. A lead 123 branches from lead 121 and connects with one pole of the operating motor 40. A lead 125 is connected with terminal post 120 of terminal block 102 and is connected with one of the contacts 93 of mercury switch 88. A lead 124 branches from lead 119 to connect with the opposite pole of the motor 40. The other contact 93 of switch 88 is connected by a lead 126 with terminal post 127 of terminal block 102. A lead 128 is connected with terminal post 127 and extends to one of the contacts 87 of the mercury switch 83. The other contact 87 of switch 83 is connected by a lead 129 with terminal post 130 of terminal block 102. Terminal post 130 is connected by a lead 131 with an overload relay or overload cut-out 132 suitably connected in the circuit and positioned within the housing 15. Overload relay 132 is also connected by a lead 133 with terminal post 104 of terminal block 102. A lead 134 is connected with terminal post 122 and connects with a manually controlled and operated switch 135 suitably mounted within the housing 15 at a point remote from the discharge opening in face plate 21. The opposite terminal of switch 135 is connected by a lead 136 with terminal post 103 of terminal block 102. Mercury switch 83 is of the three wire type which has a contact 137 at the end thereof opposite contacts 87, and one of said contacts 87 is extended at 138 to terminate adjacent contact 137. Contact 137 of switch 83 is connected by a lead 139 with terminal post 118 of terminal block 102.

The operation of the device is as follows: As-

suming that the carrier 26 has been duly loaded and that the lead lines 100, 101 have been connected with a source of power, a circuit is normally closed through line 100, lead 105, the contacts of switch 88, lead 106, lead 112, coil 61, lead 113, lead 119, lead 125, the contacts of switch 83, lead 128, lead 122, the contacts 87 of switch 83, lead 129, lead 131, overload relay 132, lead 133, to line 101. In this condition the circuit 10 serves to energize the coil 61 to draw the armature 62 into the full line position illustrated in Fig. 7, which positions arm 70 adjacent the coin guide 46. When a proper coin 59 is inserted in the coin receiver and is discharged therefrom into the coin guide 46, it depresses the arm 52 and is held in the dotted line position illustrated in Fig. 7. The tilting of arm 52 by the coin serves to shift the mercury in switch 56 to immerse the contacts 58. Consequently, a circuit in parallel to the first named circuit is then set up through lead 115 connected with lead 106 through the contacts 58 of switch 56, lead 116, lead 121, lead 123, motor 40, lead 124, to lead 118 of the previously described normally closed circuit. This serves to operate the motor 40 for the purpose of rotating the carrier 26 whereby the bottle 86 in Fig. 3 is moved to a position to be discharged through passage 36. The bottle 86 slides endwise into passage 36 and as it is moving in said 15 passage it strikes end 80 of the arm mounting switch 88 and thereby tilts said arm and said switch to open the contact between terminals 83 of switch 88. This serves to open not only the motor circuit but also the circuit to coil 61. 20 Consequently the rotation of the carrier is immediately stopped and the coil 61 is deenergized whereby the armature 62 may be pivoted to the dotted line position illustrated in Fig. 7 by means of spring 65. The arm 70 is pivoted by the armature 62 and swings to the dotted line position in Fig. 7 for the purpose of releasing coin 59 which has previously been held thereby in a position to maintain arm 52 depressed. After release the coin 59 drops into the coin chute 51 and passes 25 to any suitable coin box, whereupon the arm 52 returns to the full line position in Fig. 7 with the contact 58 of switch 56 disconnected to open the parallel motor controlling circuit. At the same time that the arm 52 is returned to its position, the arm mounting the switch 88 will return by gravity to its normal position as illustrated in full lines in Fig. 3 immediately following the passage of the bottle 86 therebeyond. It will be observed that return of the switch 88 to Fig. 3 30 position will again close the first mentioned circuit to again energize coil 61 and condition the device for a subsequent operation. In other words, the device is provided with circuits for controlling the same wherein the deposit of a coin serves to close a motor operating circuit and a discharge of an article from the carrier serves to reopen that circuit so that it is impossible for more than one article, such as bottle 86, to be discharged from the device upon any given 35 operation of the device.

In the event the carrier should be emptied the shaft 77 will be rotated by the spring 84 with the bar 80 entering within the annular guide member 35 and this will serve to tilt the switch 83 to cause the mercury to immerse the contacts 137 and 138 and to disconnect the contacts 87 of said switch. The breaking of contacts 87 of the switch serves to break or open the circuit for energizing the coil 61. At the same time the immersion of contacts 137 and 138 establishes the following

signal or warning circuit: line 100, lead 105, switch 98, lead 106, lead 108, signal 109, lead 110, lead 117, lead 139, contacts 137 and 138 of switch 83, leads 129 and 131, overload relay 132, lead 133, to line 101. In addition to the operation of the warning or empty signal 109, the deenergizing of the coil 61 serves to permit the spring 68 to shift the armature 62 and its associated parts to the dotted line position in Fig. 7. The pivoting of the member 61, 68, 69 carried by armature 62 serves to press the portion 69 thereof against the spring 78 to urge the same toward the coin receiver 19 and thereby press the pin 74 through the opening 75 into the coin passage 45 of the coin receiver. As previously mentioned, pin 74 is so positioned with relation to the coin passage 45 that it serves as a diverter for causing the coin inserted into said passage to be directed through the return passage coin return chute 20. Consequently when the device is empty any coin inserted therein will be returned to the user at coin chute 20.

The switch 135 mounted within the housing serves as a means whereby the motor 40 may be operated as desired by the person servicing the machine as for the purpose of refilling the same. Thus it will be observed that when switch 135 is closed the following motor circuit is established: line 100, lead 136, switch 135, leads 134, 121, 123, motor 40, leads 124, 119, 125, switch 88, leads 126, 128, contacts 87 of switch 83, leads 129 and 131, overload relay 132, lead 133 and line 101. It will be understood, of course, that the switch 135 is so remotely positioned from the bottle passage or article discharge opening in face plate 21 of the device that when the housing 15 has been locked it will not be possible for anyone tampering with the device to actuate and close said switch. Also, the line 105 of the circuit is preferably provided with switch 145 interposed therein. Switch 145 is adapted to be so associated and connected with the access door 160 of the cabinet 15 that when said access door is opened the switch 145 will be opened. Thus, when the access door is opened for the purpose of servicing the device or for refilling the article carrier 26, it is impossible to operate the device by means of the coin receiver 19 since the circuit thereto is dead. However, the opening of switch 145 will not interfere with the operation of the device by means of switch 135, since it will be observed from the above mentioned circuits controlled by switch 135 that the lead 105, coil 61, and switch 56 are not included in the circuit controlled by switch 135. Thus it will be observed that the switch 145 constitutes a safety feature of the device which will assure against the possibility that an operator or service man might be injured by operation of the carrier 26 while he was working therewith. For example, it will readily be observed that if an operator is filling the carrier and has his hands in one of the compartments of the carrier 26, any unexpected rotation thereof, as by insertion of a coin by a person who is unaware of the presence of the service man, might injure the arm of the operator.

Previous devices have generally had such construction as would permit the same to be tampered with to obtain unauthorized discharge of the article to be vended by manipulation of the machine as by shaking or tilting thereof. In the instant device the use of the mercury switches 56, 83, 88, and 98, which are of a character requiring liquid to be in a stationary predetermined position in order to close said switches, 75

and which are relatively perpendicularly arranged (see Fig. 2) effectively prevents the possibility of unauthorized discharge of articles by shaking or tilting or manipulating the device. 5 In other words, at any time when the device might be shaken or tilted, some one of these switches is almost certain to be positioned in a manner to cause the mercury thereof to be spaced from the switch contacts and thereby to open the switch circuit. More particularly it will be noted that if the mercury switch 98 is open, the entire operating circuit is immediately opened. If the device should be tilted while the mercury switch 56 is in a closed position, the tilting thereof may open the motor circuit and immediately stop operation of the device. The normally closed switch 88 may by tilting or shaking of the device be opened and this operation will also deenergize the motor and additionally deenergize the coil 61. The same function is achieved by tilting of switch 83 as by tilting of switch 88 inasmuch as switches 88 and 83 are in series in the control circuit.

A further advantage of the device will be observed to be the fact that its operation is entirely automatic, and, aside from the insertion of a proper coin in the coin receiver 19, the user need perform no other manual operation.

An additional advantage of the device resides 30 in the fact that the construction of the cylindrical article container is of such character as to compactly hold the articles to be dispensed and also to so hold the same that the articles are retained in operative position despite rough 35 handling as by shaking or tilting the device. Hence the simplicity of the carrier, coupled with the automatic character of the operation thereof, produces a device which is substantially trouble free, tamperproof, compact, inexpensive, easy to operate, and of highest efficiency for its intended purpose.

A modified embodiment of the invention incorporating certain additional advantages is illustrated in Figs. 11 and 12. In this embodiment of the invention, the member 80 which is adapted to engage the bottles upon the guide 35 for the purpose of controlling the position of switch 83 has mounted thereon an arm 150 pivoted at 151 to a depending bracket member 152 carried by the guide 35. The arm 150 is connected with a tension spring 153 at 154. The opposite end of the spring 153 is connected to a part 155 projecting at an angle from an elongated rigid rod 156, which is suitably mounted 55 within the cabinet and whose forward end terminates adjacent the access door of the cabinet. Rod 156 is mounted for longitudinal movement under the influence of a spring 157 to be urged forwardly as viewed in Figures 11 and 12. Rod 60 156 is normally held in the position illustrated with respect to the remaining parts of the device when the access door of the cabinet 15 is closed. Rod 156 passes closely adjacent the upper end of chute 36, whose upper edge is 65 cut away at 36' to receive a plate 158 mounted upon the rod 156. In other words, when the access door of the cabinet is opened and the rod 156 shifts forwardly, the plate 158 will enter the slot 36' and partially span the chute 36 whereby the bottles upon the guide 35 will ride past the chute 36 without being discharged therefrom, as illustrated in Figure 11. The spring 153 serves the same function as the spring 84 of the preferred embodiment, namely to urge the member 80 into the guide 35 when no bot-

ties are retained therein. Hence, it will be observed that when the carrier 26 becomes empty, the spring 153 will pivot the parts including member 80 into the guide 35 and will thereby tilt switch 83 to close the contacts 131 and 138 of said switch. However, when the bar 156 shifts forward, under the influence of spring 157 upon opening of the access door 126, tension of the spring 153 is released and member 80 is overbalanced by the weight of switch 83 and associated parts to again tilt switch 83 to close the circuit between the contacts 87 or switch 83. Hence, it will be observed that the opening of the access door automatically conditions the circuit so that it is adapted to be closed through the switch 135. This eliminates the necessity of manually tilting the switch 83 during the time that switch 135 is held closed, as is required in the preferred embodiment of the invention.

I claim:

1. In a dispensing machine, a housing having a discharge passage, an article carrier shiftable to successively discharge articles into said passage, a drive motor therefor, a normally closed operating circuit, means for connecting said motor in said circuit for operation of said carrier to discharge one article only, and a pair of normally closed mercury switches in said circuit, arranged in perpendicular relation whereby at least one of said switches will open to break said circuit when said housing is tilted or shaken.

2. In a dispensing machine, a housing having a discharge passage, a cylindrical article carrier rotatable in said housing on an inclined axis, with its lowermost end juxtaposed to said passage, radial longitudinal partitions in said carrier defining a plurality of article receiving compartments and projecting longitudinally beyond the lower end of said cylindrical carrier whereby each of said compartments is open at its circumference at its lower end, an end wall mounted on the projecting ends of said partitions, and an annular retainer member fixedly carried by said housing and encircling the projecting portion of said partitions, said retainer having an opening in the lower portion thereof registering with said discharge passage.

3. In a dispensing machine, a housing having an article discharge passage, an article carrier rotatably mounted in said housing on an inclined axis, said carrier having a plurality of elongated radial compartments therein each closed at its lower end and for the major portion of its outer side and adapted to receive a plurality of articles, said carrier having a restricted circumferential opening adjacent its lowermost end, an annular retainer fixedly carried by said housing and encircling said carrier at said circumferential opening to retain the lowermost article in each compartment, said retainer having an opening in the lower portion thereof registering with said discharge passage.

4. A dispensing machine as defined in claim 3, including a divider fixedly carried by said housing adjacent said passage and extending into said carrier between the two lowermost articles in the compartments adjacent said discharge passage to permit discharge of only one article through said retainer opening.

5. A dispensing machine as defined in claim 3, and a member pivotally mounted on and projecting into said passage to be shifted by an article passing therethrough, and a mercury switch mounted on said member to be tilted upon shifting of said member.

6. A dispensing machine as defined in claim 3, wherein said retainer is spaced from said carrier adjacent said discharge passage, and tiltable means mounting a mercury switch and adapted to extend laterally within said retainer when said compartments adjacent said discharge passage are empty, said articles normally positioning said means outwardly of said retainer.

7. In a dispensing machine, a housing having a discharge passage and an access door, an article carrier actuatable to discharge articles into said passage, a spring pressed member normally engaging said access door, and a barrier member carried by said last named member and normally positioned clear of said discharge passage, said spring pressed member being shifted by its spring when said door is opened to position said barrier across said discharge passage.

8. In a dispensing machine, a housing having a delivery chute and an access door, an article carrier actuatable to discharge articles into said chute, a spring pressed member normally engaging said door to be held thereby in one position and being shifted by said spring transversely of said chute to a second position when said door is open, and a barrier carried by said member, said barrier extending across the intake end of said chute when said member is in second position and being laterally spaced from said chute when said member is in first position.

9. In a dispensing machine, a housing having an article discharge passage and an access door, an inclined article carrier rotatable in said housing, a fixed article guide juxtaposed to said carrier and having an opening communicating with said passage, said carrier delivering articles to said guide and propelling articles thereon to said opening, a mercury switch, an unbalanced pivoted member mounting said switch and having a portion adapted to engage articles on said guide adjacent said opening, and spring pressed means for urging said mounting member toward said articles when said access door is closed, said last named means including an element pressed against said door and shiftable to release the tension of said spring upon said unbalanced member when said door is opened, said unbalanced member holding the switch in the same position when said spring tension is released as when said member engages articles on said guide.

10. In a dispensing machine, a housing having an article discharge passage and an access door, a guide on which articles may be propelled to said passage, an article carrier discharging articles on said guide and propelling articles thereon, a mercury switch, a normally unbalanced pivoted member adapted to engage articles on said guide and having two opposed switch controlling positions, and means associated with said door for applying spring tension to said member to overcome the unbalance thereof when said door is closed, said member being pivoted in unbalanced position against the action of said spring by articles on said guide.

11. In a dispensing machine, a housing having an article discharge passage; an article carrier rotatably mounted in said housing on an inclined axis, said carrier including a plurality of elongated radial partitions, closure means spanning the outer edges of said partitions and terminating in spaced relation to the lower ends of said partitions, and an end plate secured to the lower ends of said partitions; and a sta-

tionary article retainer carried by said housing and encircling said carrier intermediate said closure means and end plates, said retainer having an opening registering with said discharge passage.

12. In a dispensing machine, a housing having an article discharge passage; an article carrier rotatably mounted in said housing on an inclined axis, said carrier including a plurality of elongated radial partitions, closure means spanning the outer edges of said partitions and terminating in spaced relation to the lower ends of said partitions, and an end plate secured to the lower ends of said partitions; and a stationary article retainer carried by said housing and encircling said carrier intermediate said closure means and end plate, said retainer having an opening registering with said discharge passage, and a divider fixedly carried by said housing and extending into said carrier adjacent said discharge passage adjacent the lower end of said closure means, said partitions having radial openings receiving said divider.

13. In a dispensing machine, a housing having an article discharge passage; an article carrier rotatably mounted in said housing on an inclined axis, said carrier including a plurality of elongated radial partitions, closure means spanning the outer edges of said partitions and terminating in spaced relation to the lower ends of said partitions, and an end plate secured to the lower ends of said partitions; and a stationary article retainer carried by said housing and encircling said carrier intermediate said closure means and end plate, said retainer being spaced outwardly from said carrier adjacent said discharge passage, shiftable means spring pressed to extend laterally into said retainer and normally positioned outwardly of said retainer by articles bearing on said retainer on the approach side of said passage, and control means actuated by movement of said shiftable means between its spring pressed and normal positions.

CHARLES C. KUHL.
